UNITED STATES PATENT OFFICE

ARTHUR S. WATTS, OF COLUMBUS, OHIO

TUNNEL KILN AND DRAFT CONTROL FOR THE SAME

Application filed October 28, 1930. Serial No. 491,795.

In the drawings:

Figure 1 is a longitudinal vertical section through a tunnel kiln embodying my invention.

5 Figure 2 is a similar view of a tunnel kiln, the arrows indicating the direction of natural draft from entrance to exit.

Figure 3 is a transverse longitudinal view of Figure 2.

10 Figure 4 is a vertical longitudinal view of a tunnel kiln with stack at entrance end of kiln, the arrows indicating direction of artificial draft toward the entrance end of kiln.

Figure 5 is an enlarged detail side elevation of a portion of Figure 1.

15 Figure 6 is a top plan view of Figure 5.

Figure 7 is a vertical transverse sectional view of Figure 6 on the line 7—7, Figure 5.

The reference numeral 8 designates a continuous tunnel kiln, having the entrance end 9 and the exit 10. This kiln has a heating up zone 11, a high temperature zone 12, and a cooling zone 13. It will be understood that there may, according to my invention, be one

20 or more high temperature zones. The natural draft in a tunnel kiln is from entrance to exit as indicated by the arrows 14 in Figure 2. In order to carry the draft of heat from the high temperature zones toward the entrance

25 end of the tunnel and thus heat up the ware which is traveling toward the high temperature section of the tunnel, it is customary to provide a stack, or other artificial draft element 15 at the entrance end of the tunnel and

30 thus reverse the natural course of draft travel as indicated by the arrows 16 in Figure 4. This also draws the heat, which is radiated from the ware 18, and conveyors 19, in the cooling end 13 of the tunnel, through the

35 high temperature zone 12, so that all heat not lost by radiation passes over or among the ware being heated up, in the heating up section 11, thus conserving heat. The amount of draft provided will control the rate at

40 which the hot air will travel toward the entrance end 9 of the kiln.

45 The primary object of my invention is to provide means of controlling temperature development and temperature distribution in 50 ceramic tunnel muffle kilns within which the

ware is transported through various zones of different temperatures which I will now describe which I have discovered and proven.

The invention provides for the introduction of a blast of air from below or at the 55 sides of the cars 19, or other conveying devices, into the area above the conveying devices 19 on which the ware is carried, the said blast of air being projected by the air blast device 20, connected with the compressed air line 21, into the currents of air (see arrows 16) induced by the stack 15, or other artificial draft, and toward the entrance 9 of the tunnel. This acts as a counter-draft and damper to the natural draft and accelerates the artificial draft, and causes the heat to bank up within a limited area immediately preceding the point of entrance of said draft of air and toward the entrance and develops an abrupt temperature drop immediately beyond the point of entrance of said draft of air and toward the entrance end of the kiln.

70 I also provide for the introduction of a blast of air, by means of the air blast 22, on a level with or above the level of the top of the car, or other conveying device 19, the said blast of air being directed toward the entrance end of the kiln so that the natural draft which travels from the entrance end through the high temperature zone, or zones, 75 and toward the exit end of the tunnel is nullified, and the temperature developed in the high temperature zone is prevented from traveling toward the outlet end of the tunnel and by a proper control, by valve 23, of the amount of air blast or counter-draft provided the heat is banked up in the high temperature zones and only such amount travels toward the entrance 9 of the tunnel, as is necessary for the proper heating up of the cars 80 and the ware they carry.

85 I further provide the kiln with another air blast 24, controlled by the valve 25. The introduction of a counter-draft blast of air just above described and providing the kiln with an auxiliary ventilator 26 adjacent to the point of entrance of this blast 24 and slightly nearer the entrance end of the tunnel results in the establishment of a draft in the tunnel 90 at right angles to the line of travel of the ar- 100

tificial and natural drafts, and by thus diverting a limited portion of the heat existing between the point of entrance of the blast 24 and the ventilator, a zone of heat from the high temperature zone beyond this temperature drop is regulated.

The high temperature zones are provided with muffle walls 27. The air blast 20 is controlled by the valve 28.

10 I do not claim the apparatus herein shown for setting up a draft longitudinally in the kiln counter to the natural draft from the entrance end of the kiln as that is the invention of Homer A. Evans, who has filed an application for patent thereon, Serial No. 491-
15 793, my invention consisting in utilizing the Evans' invention in combination with the auxiliary ventilator and blast 24, whereby a zone of lower temperature is developed and
20 the penetration of heat from a high temperature zone beyond this temperature drop is regulated.

What I claim is:

1. In a tunnel kiln consisting of a heating
25 up zone, high temperature zones, and a cooling zone, through which ware travels, and an artificial draft element, an auxiliary ventilator for the tunnel between the high temperature zone and the entrance of the tunnel,
30 means to create a draft through the tunnel into said auxiliary ventilator and at substantially right angles to the line of travel of the artificial and natural drafts of the tunnel thereby diverting a limited portion
35 of heat existing between the point of entrance of the blast and ventilator whereby a zone of lower temperature is developed and the penetration of heat from a high temperature zone beyond this temperature drop is regulated.

40 2. In a tunnel kiln consisting of a heating up zone, high temperature zone, and a cooling zone, through which the ware travels, an artificial draft element at the entrance
45 end of the tunnel, means for controlling temperature development and temperature distribution in said tunnel including an air blast element to project air blasts into the currents of air induced by the said artificial draft toward the entrance of the tunnel to cause the air to bank up within a limited area and develop an abrupt temperature drop beyond the point of entrance of said draft of air and toward the entrance end of
50 the tunnel, an air blast element for directing a blast of air toward the entrance end of the tunnel to nullify the natural draft which travels from the entrance end toward the exit end of the tunnel, an auxiliary ventilator
55 for the tunnel between the high temperature zone and the entrance end of the tunnel, but at a point nearer the high temperature zone than the said artificial draft element, and an air blast element to introduce an air blast into
60 the tunnel at right angles to the line of travel

of the artificial and natural drafts and diverting a limited portion of the heat existing between the point of entrance of the blast and said ventilator, whereby a zone of lower temperature is developed and penetration of heat from the high temperature zone beyond this temperature drop is regulated.

In testimony whereof I affix my signature.

ARTHUR S. WATTS.
